RICHARD S. COOKSON AND HENRY COOKSON, OF PHILADELPHIA,
PENNSYLVANIA.

JACQUARD MECHANISM FOR LOOMS FOR WEAVING PILE FABRICS.

No. 831,144.

Specification of Letters Patent.

Patented Sept. 18, 1906.

Application filed May 12, 1905. Serial No. 260,081.

To all whom it may concern:

Be it known that we, RICHARD S. COOKSON and HENRY COOKSON, citizens of the United States, residing at the city of Philadelphia, in the county of Philadelphia and State of Pennsylvania, have jointly invented 5 certain new and useful Improvements in Jacquard Mechanism for Looms for Weaving Pile Fabrics, of which the following is a specification.

Our invention has relation to a Jacquard mechanism for employment in the fabrication of pile fabrics, especially adapted for the production of a Brussels-carpet fabric such as has been shown and described in the United States Letters Patent No. 731,433, granted to us under date of June 23, 1903; and in such connection it relates more particularly to the arrangement and form of 20 needles for manipulating the pile or face-threads in the fabrication of such a fabric, as well as other pile fabrics.

Hitherto all the needles employed in a Jacquard mechanism for employment in the fabrication of pile fabrics arranged in a row were each provided with an eye and a loop, the eyes of the needles serving to control cords normally unlocked from the trap-board of the Jacquard mechanism and the 25 loops of all the needles serving to control additional cords normally locked to the trap-board. In a ten-needle Jacquard mechanism, for instance, twelve cords and their respective ends or warp-threads were controlled by the needles, which threads were 30 divided in sets of six warp-threads, each set 35 of six warp-threads passing through a dent in the reed. The arrangement of the needles was such that the first five needles controlled 40 six ends in the first dent and the remaining five needles controlled the six ends in the adjacent dent of the reed, thereby requiring two dents for each row of needles. The single warp-threads from six frames each 45 supplied two ends, one end for each dent of the reed. If the six threads in each dent were divided in pairs of threads, each pair, for example, had a distinct color—for instance, green, brown, and écrù. It was 50 found that by the foregoing-described arrangement of the needles in each dent of the reed either a single warp-thread or a pair of different-colored warp-threads, or a pair of green or brown colored warp-threads were

raised. It was, however, impossible to raise 55 two écrù-colored warp-threads in each dent, either alone or in conjunction with other colored warp-threads, since one of each of these threads is supplied by the bottom frame, the cords of which are controlled by 60 the loops of all of the needles, one needle in each set of five needles being operated to lock its end controlling an écrù-colored warp-thread supplied by an intermediate frame. Hence this needle, by means of its loop, simultaneously 65 unlocked the cord from the trap-board controlling one of the ends or warp-threads of the bottom frame, and for this reason only one écrù-colored warp-thread of the intermediate frame could be raised in a 70 dent of the reed.

The principal objects of our present invention are, first, to overcome the above-described disadvantages and to so arrange the needles—for instance, in a ten-needle 75 Jacquard mechanism—that two ends or a pair of warp-threads of all the varied colored pairs of warp-threads may be raised in addition to one or more warp-threads of different-colored warp-threads, and, second, to so 80 arrange the needles that certain needles thereof actuate one cord and warp-thread only and certain other needles thereof actuate two cords and warp-threads.

The nature, scope, and characteristic features of our invention will be more fully understood from the following description, taken in connection with the accompanying drawing, illustrating in diagrammatic view a portion of the Jacquard mechanism, ten needles arranged therein, and the manner of connecting and actuating twelve ends or warp-threads with the same embodying the main 90 features of our invention.

Referring to the drawing, *a* represents the 95 board from which the cords *c'* to *c¹²*, inclusive, are suspended.

d is the trap-board, which is raised and lowered by means (not shown) and which actuates the cords passing therethrough by engaging their knots *c¹³*, when the cords engage the eye extensions *d²* thereof. Each of the cords *c'* to *c¹²*, inclusive, pass through the cumber-board *o* and engage a single end or warp-thread *g g'*, *b b'*, and *e e'* by means of an eye *c¹⁴*. Each cord at its end is provided with the usual weight or lingo *c¹⁵*. These twelve ends come from six frames *f* to *f⁶*, in-

clusive, each frame supplying two ends g g' , b b' , and e e' , one end for each dent r' or r^2 of a reed r . In order to raise certain colored ends to produce, for instance, the coloring effect in 5 the Brussels-carpet fabric shown and described in said United States Letters Patent No. 731,433, two ends in the sets of six ends are of the same color—that is, green, brown, and écrù. In order to properly manipulate 10 the twelve ends either singly, in pairs, or in sets of three or more threads, the needles 1 to 10, inclusive, are arranged in the following manner: All the needles employed are provided with an eye i , through which the first 15 ten cords c' , c^2 , c^3 , c^4 , c^5 , c^6 , c^7 , c^8 , c^9 , and c^{10} , are conducted. In addition to the eyes i , the needles 4 and 5 and 9 and 10 are provided with loops i' , arranged intermediate of the eyes i and hooks i^2 thereof. Through these loops i' 20 the remaining two cords c^{11} and c^{12} , controlling the ends e and e' of the bottom frame f^5 , containing écrù-colored yarn, are conducted. As shown in the drawing, the cords c^{11} and c^{12} normally pass through the eye extensions d^2 25 of the trap-board d and are therefore locked to the same, while the cords c' to c^{10} , inclusive, normally pass through the eyes d' of the trap-board d and are therefore not locked to the said trap-board d . This board d will therefore raise the cords c^{11} and c^{12} , and the écrù-colored ends e and e' of the bottom frame f^5 , one in each dent r' or r^2 of the reed r , when the needles are not operated. This actuation of the cords c^{11} and c^{12} will take place 30 only when the Jacquard card k , held opposite the needles by the Jacquard cylinder l , is provided with the holes k' , in which instance the needles are not actuated from left to right in the drawing, but remain in their 35 inoperative position. In order to render these cords c^{11} and c^{12} inoperative, it is necessary to provide blanks in the card k opposite the needles 4 and 5 and 9 and 10—that is, these needles are shifted by the cylinder l 40 from left to right, by which movement the cords c^{11} and c^{12} by means of the loops i' are brought out of engagement with the contracted extension of the eye d^2 and into engagement with the eye d' . By the shifting of 45 the needles 4, 5, and 9 and 10 the pair of écrù-colored ends e and e' of the bottom frame f^5 is not raised by the trap-board d ; but in its place the cords c^7 and c^9 and c^8 and c^{10} are actuated, which raise a single green and brown 50 colored end in each of the dents r' and r^2 of the reed r . The raising of each of these ends is accomplished since the cords c^7 , c^9 , c^8 , and c^{10} have been shifted into engagement with the eye extensions d^2 of their respective eyes 55 d' in the trap-board d . By this arrangement of the needles and ends it is possible to raise in each set or weave of the pile fabric to be produced, either the green, brown, or écrù colored ends or a combination of these ends 60 by arranging blank spaces in the card k op-

posite their respective needles. The pile fabric (not shown) will have in this instance two colored ends arranged side by side in the fabric, while beneath each end will be buried four ends not raised by the needles. All the 70 needles after being actuated by the card k and the cylinder l are shifted back into their normal position by the shifting-board m in a well-known manner, which movement by the needles 4 and 5 and 9 and 10 and their loops 75 i' is utilized to bring the cords c^{11} and c^{12} , controlling the écrù-colored yarns e and e' of the bottom frame f^5 , back into engagement with their respective eye extensions d^2 in the trap-board d when the same have been disengaged therefrom. 80

Any combination of the green, brown, and écrù colored ends may be raised as long as single ends or a pair of green and brown colored ends are to be raised in each dent r' or 85 r^2 , in which instance the cords c' to c^{10} , inclusive, are shifted by the needles into engagement with the extension d^2 of their respective eyes d' in the trap-board d , by which movement the cords c^{11} and c^{12} are simultaneously disengaged from the trap-board d . 90 When, however, two écrù-colored ends in each of the dents r' or r^2 are to be raised, it is only necessary to actuate the needles 3 and 8 and to permit all other needles to remain inactive. The needles 3 and 8 must be shifted to lock their cords c^5 and c^6 to the trap-board d , each of which controls one end of the écrù-colored ends of the top frame f^2 . The écrù-colored ends of the bottom frame f^5 , by 95 means of their cords c^{11} and c^{12} , are normally locked to the trap-board d , and thus require no actuation by their respective needles. The trap-board will thus raise two écrù-colored ends in each of the dents r' and r^2 of 100 the reed r . Instead of raising two ends in each dent r' or r^2 of the same color three similarly-colored ends and one or more other colored ends may be simultaneously raised in the dent through proper manipulation of the 105 needles by the Jacquard card k and shifting-board m . The loops i' (shown in the drawing) are of a size adapted to disengage the cords c^{11} and c^{12} from the trap-board d when actuated by the needles 4 and 5 and 9 and 10, respectively. All other needles are 110 shown as being minus such a loop i' in order to permit of the manipulation of six ends by five needles in each dent of the reed r and of the raising of the certain colored ends of the 115 bottom frame f^5 . The object of not actuating the cords c^{11} and c^{12} by the needles 1, 2, 3, 6, 7, and 8 can also be accomplished by 120 making the loops i' of such a size or length as to prevent an operation of the cords c^{11} and c^{12} when their respective needles are shifted by the Jacquard card k and board m . Thus 125 the needles 1, 2, 3, 6, 7, and 8, if desired, may be provided with such long loops i^3 , as shown in dotted lines. In the present instance a 130

Jacquard mechanism with ten needles has been shown, five of which actuate six cords and ends connected therewith in a dent of the reed r . However, by the arrangement 5 and form of the needles shown eight needles may readily actuate ten cords and ends—that is, five cords for each dent of a reed r .

Having thus described the nature and objects of our invention, what we claim as new, 10 and desire to secure by Letters Patent, is—

1. In a Jacquard mechanism for looms for weaving pile fabrics, two series of needles arranged in a single row, in which one series have eyes adapted to move a single cord to control a warp-thread, and in which the other series have eyes and loops adapted to move two cords to control their warp-threads independently of the series of needles moving the single cord to control its warp-thread. 15

2. In a Jacquard mechanism for looms for weaving pile fabrics, two series of needles arranged in a single row, the needles of one series having eyes to move one cord to control a warp-thread, when shifted in opposite di- 20

rections, and the other series of said needles 25 having loops in addition to eyes to move certain additional cords to control two warp-threads, when shifted in opposite directions.

3. In a Jacquard mechanism for looms for weaving pile fabrics, two series of needles, 30 one series of needles having eyes and the other series having eyes and loops, a trap-board, cords passing through the eyes of said needles and normally unlocked from the eyes of said trap-board and the other cords passing 35 through the loops of said needles and normally locked to said board, the needles having eyes only, adapted to move their respective cords independently of the other needles having eyes and loops. 40

In testimony whereof we have hereunto set our signatures in the presence of two subscribing witnesses.
